VERTICAL COIN COUNTING TUBE

Robert T. Allen, 132 Pineview Terrace, Plainfield, N.J.
Filed Dec. 18, 1962, Ser. No. 245,464
2 Claims. (Cl. 206—83)

This application is a continuation-in-part of copending application Serial No. 161,778 filed on December 20, 1961, now Patent No. 3,071,243, granted January 1, 1963, by Robert T. Allen.

This invention deals with a vertical counting tube for coins. More specifically, it relates to a vertical coin counting tube having stepped sections and interiorly disposed staggered ledges for limiting entry, into each section, of coins in excess of the counted number.

There have been disclosed in the art numerous counting trays in which coins are to be laid on their edges and counted by stacking in these trays. Unfortunately, such trays are bulky and difficult to handle so that their use in buses, for example, has never been undertaken. Demand has arisen for a vertical counting device of a simple type, but there has been no success in developing such a unit.

The object of the present invention is to provide such a device which will count coins accurately in the vertical direction and which can be made cheaply and which can be used without any complicated manual or mechanical operations. In copending application, Serial No. 161,778, filed on Dec. 20, 1961, by Robert T. Allen, a vertical coin counting tube similar to the one of the present invention, is described. The present application involves new and important improvements thereof, as will be apparent from the description which is to follow.

The invention will be more readily understood by reference to the accompanying drawings in which a preferred embodiment is disclosed, and in which FIGURE 1 illustrates a rear view of the counting tube, while a side view thereof is depicted in FIGURE 2. A vertical cross-sectional view showing the interior rear portion of the same tube is presented in FIGURE 3. FIGURE 4 shows a similar view of the front portion thereof. A top view thereof is illustrated in FIGURE 5. A cross-sectional side view of the same tube is shown in FIGURE 6, while FIGURE 7 depicts the same view when the tube is filled with coins. FIGURE 8 presents a schematic top view of the tube showing that the coin must be tilted to be inserted therein. A schematic phantom front view of the tube is shown in FIGURE 9 to illustrate the manner of stacking the coins therein. FIGURE 10 depicts a side elevational cross-sectional view of another modification of a tube wherein the tube sections are stacked along the same vertical axis. Similar numerals refer to similar parts in the various figures.

Referring again to the drawings, numeral 1 designates generally a counting tube of the present invention having sections 2, 2', 2'', etc., each successive section being stepped incrementally forward from the one above (FIG. 2). Since backs of the steps define the rear boundary, and steps 3 the front boundary of each section the two boundaries are separated at the sides at 6 by a distance equal to the wall thickness (FIG. 6) of the tube. Each section 2, 2', 2'', etc., has a height such as to contain a counted number of coins, such as 5, but preferably not over 10. Since the stepwise design would tend to make tube 1 unstable as to balance, a vertical balancing fin 4 may be provided to enable tube 1 to rest stably on its bottom edge 8.

Coin bottom 9 (on which the first coin 23'' falls) is slanted at a sharp angle, (FIG. 7) such as an angle of 45°, and all sections 2, 2', 2'', etc., are slanted so that

2

their boundary edges 24 (FIG. 6) are parallel to bottom 9. These slanted sections of tube 1 are of such height that the loss in thickness of coins (as compared to newly minted coins) in each stepped section is less than the thickness of an average (run-of-the-mill) coin. Thus, as will be outlined further, such stepping at these intervals in the slanted stack of coins "absorbs" the thickness loss for each section, whereby additive accumulation of thickness loss is avoided, provided means are present to place each first coin of the next superimposed section in its proper position. "Thickness loss" is defined here as the loss in thickness suffered by the coin during use since coinage. It has been found that, even with such stepped section arrangement, extra coins (i.e., those over the counted number intended to be contained per section) will fill in the free space provided by "thickness loss" of the already-stacked coins, resulting in an inaccurate count of the coin stack. In accordance with the present invention, novel staggered ledge means are provided at the section junctions to alternately tilt the stacks in opposite directions, to guide the coins into their respective stacks, to prevent entry of extra coins into the free space, and to shift the first coin into its new position as soon as one stack is accurately filled, whereby an accurately-counted tubeful of coins is made available, without jamming, for packaging or wrapping, when discharged by mere inversion of the tube.

Boundaries 24 of the lower sections (i.e., those sections bounded by top section 2 and the bottom of bottom section 2'') are provided with inwardly-projecting ledges 11, 12, 11', 12' (FIG. 3), which ledges are also slanted to be parallel to bottom 9, or even may be more slanted. These ledges, which are disposed at the section boundaries and are thus substantially parallel to each other at their outer boundaries 24, extend for a short distance between the middle of the rear and the middle of the side of tube 1. The uppermost ledge 11 begins to emerge gradually from the inner wall at, say 25' (FIG. 3), and then widens to about the center between mid-rear and mid-side at, say 26, when it forms a vertical projecting wall face, say 13. Thereafter, at point 17 about half-way of the width of face 13, the edge of ledge 11 is cut downwardly to form a chamfered ledge 15, after which the ledge and projecting face or wall 13 are cut off practically in a radial cut to form a side 21 connecting with the wall of the tube section 2'. In the uppermost section 2, a similar projecting wall 13' and ledge 11' are provided between the middle of the rear and middle of the side of tube 2, with the exception that ledge 11'' is not provided with a chamfer (such as chamfer 15), but is flush with the top edge 7 of the tube. As to the lower ledges 12, 11' and 12', they are similar to ledge 11, with the exception that these ledges (including ledge 11') are successively in image relation to each other. Also, it will be noted that the positions of all of the ledges are staggered so that the first ledge 11'' is disposed at the left and the second ledge 11 at the right, the third ledge 12 at the left, and the fourth 11', at the right. As a result of this construction, coins 23 (FIG. 9) inserted at an angle to tube 1 will fall therein and, due to the positions and incline of ledges 11, 12, etc., as well as chambers 15, they will not be caught on these protrusions, but will fall to the lowest point in the tube. After the bottom section 2'' is filled with the counted number of coins 23a (say 10 coins), the eleventh coin will fall on ledge 12' and the coins in the second stack 23b will be tilted downwardly toward the right. After this is filled with the counted 10 coins, the eleventh will fall on ledge 11' and the coins 23c in that stack will be tilted downwardly toward the left, and so on. Because of this positioning, it will be noted from FIGURE 8 that the tube inner sec-

tions are not circular in cross-section, but are of oval shape, being wider at their sides $1'b$ than at their front-to-rear dimension $1'a$. In the tube of FIGURES 3-4, the outer diameter is circular, so a thicker front portion 28 is provided on the inside of the front (FIG. 4), and the coins could be inserted through the wider side portions 51 and 52. In the case of one-cent pieces, for example, the increase in thickness of portion 28 (in excess of the tube wall thickness) would be about 0.1". Ledge 11 projects about $\frac{1}{32}$ " from the inner wall and has an overall length of about $\frac{5}{32}$ ".

As may be seen from FIG. 9, the first stack 23a of coins consists of the first coin (which is coin 23" in FIG. 7, and which lies flat against the bottom 9 or 9'), as well as four more coins superimposed thereover. When the sixth coin (which is coin 23' in FIG. 7) falls into the tube, there is insufficient room for it in the remaining space in section 2", so that it falls on ledge 12', whereby it is tilted at a slight angle from the coins in stack 23a. Thereafter, four additional coins fall flat over coin 23', forming the second stack of coins. When the eleventh coin falls into the tube, there is insufficient room for it in the space remaining in the last-filled section, so that it falls upon ledge 11', and it is tilted at an angle away from the tilt of the coins in the second stack, etc. Finally, when the uppermost coin of the uppermost stack is inserted in the tube, that coin is practically flush with the upper edge 7 of the tube, indicating that the tube has a full count of coins.

The tube depicted in FIGURES 1-7 is provided with vertical slots 30, 30a, 30b, 30c and 30d which are cut into the front wall of each section 2a, 2'a, 2''a, etc., above steps 3 between the upper sections and, of course, above bottom edge 8 of the lowest section. This enables observations of the coins in all sections and also permits insertion therein of a pencil tip or stylus to loosen any coins which may become jammed.

In FIGURE 10, a counting tube 1a is shown wherein each section is disposed over the lower section in a manner so that the front and back corners 3 and 5, respectively, are in vertical alignment on the same vertical axis, so that the tube is more compact laterally and does not require the support or fin 4. The outer wall of uppermost section 2 is also provided with a bead or shoulder 40 at least partly around section 2 and near edge 3a to enable engagement of inwardly-curved flange 41 of cap 42 which is designed to be snapped onto the top of counting tube 1a and serve as a cover therefor. Coin bottom 9' of tube 1a also may be formed in the shape of a hollow cap having inwardly-curved flange 43 which snaps over shoulder 44 and serve as a cover for the bottom. Downwardly-directed tube extension 45 may be provided with bottom flange 46 to enable standing of tube 1a thereon. Thus, it is seen that tube 1a may serve both as a counting tube and wrapper and may be sent to the bank in that manner. Or, bottom 9' and its tube extension may be substituted by a cap similar to cap 42. It is, of course, understood, that tube 1a would be returned by the bank,

or the latter could furnish such tubes and caps to its customers.

When in use, the tube is held vertically or placed on its bottom 8. Coins are inserted into top 7 in tilted position, the first coin landing on slanted coin bottom 9 or 9'. When the counted number (say 10) of coins 23a has filled section 2", the sixth or eleventh coin 23' (as the case may be) will fall on ledge 12' which is disposed to the left of the center of the tube, but in the rear half thereof. This is due to the fact that the edge of an excess coin will hit section boundary protruding edge 3a and the opposite edge of the coin will fall on ledge 12' which positions the coin for the next counted coin section, and so on. The alternating tilting of the stacks caused by staggering of the ledges avoids excessive build-up of angularity, i.e., it tends to minimize the increase in vertical slant of upper coins 23 over the lower coins 23" and also effects better positioning in the arcuate filling of the sections.

When the tube is entirely filled with coins, the addition of an extra coin in the upper section 2 of the tube will cause the coin to slide off upper edge 7 which thus will prevent entry of further coins into that section.

After the tube is filled with coins, as shown in FIGURE 7, it is inverted and the coins are poured into a wrapper in accurately-counted condition. The other tube shown in the drawings is handled in a similar manner, except as modified by the changes indicated.

I claim:

1. A coin counting tube, comprising, a vertical layer of hollow, parallel slightly ovate cylindrical sections, including top and bottom sections disposed in forwardly- and downwardly-slanted and superimposed relation to each other, the height of each section being such that the loss in thickness of the coins therein is less than the thickness of a run-of-the-mill coin, a flat coin bottom for the bottom section, similarly slanted in said tube and to the same degree, a downwardly-slanted ledge and projection thereunder protruding inwardly from the upper inner back boundary of each section, said ledge and projection being disposed in staggered and image relation to the next succeeding ledge between the back and side centers in a manner such that extra coins of an upper section will fall thereon and be tilted in a direction opposite to that of the coins in the lower section, said ledge in each section being flush with the upper edge of its section.

2. A coin counting tube according to claim 1 in which all ledges, except the upper ledge, are provided with a downwardly-directed chamfer on their lower portions.
